CLAIM

The ornamental design for a wristwatch, as shown and
described.

DESCRIPTION

FIG. 1 is a top plan view of a wristwatch showing my
new design;

FIG. 2 is a right side elevational view thereof;

FIG. 3 is a bottom plan view thereof;

FIG. 4 is a left side elevational view thereof;

FIG. 5 is a rear elevational view thereof, the front view
being a mirror image thereof;

FIG. 6 is a top plan view of another embodiment of my
new design of FIGS. 1-5, all other views being identical
thereto.

FIG. 1

FIG. 2

FIG. 3

FIG. 4

FIG. 5
